UNITED STATES PATENT OFFICE.

LILLIAN D. STOCKLE, OF VINELAND, NEW JERSEY.

PORTABLE STANDARD AND CANOPY SUPPORT FOR INSECT SCREENS, NETTING, AND THE LIKE.

1,409,609.

Specification of Letters Patent. Patented Mar. 14, 1922.

Application filed August 17, 1921. Serial No. 492,981.

To all whom it may concern:

Be it known that I, LILLIAN D. STOCKLE, a citizen of the United States, residing at Vineland, in the county of Cumberland, State of New Jersey, have invented a new and useful Portable Standard and Canopy Support for Insect Screens, Netting, and the like, of which the following is a specification.

10 My invention consists of a novel construction of a portable standard and canopy support for insect or mosquito screens or netting and the like, wherein I provide a suitable standard having means attached there-
15 to for supporting a shelf or shelves, and an electric light, the upper portion of said standard being provided with a novel construction of a head block, which supports a novel construction of laterally extended
20 jointed bars, which when assembled constitute a lateral frame, which is so constructed that when the bars composing the frame are in their laterally extended position and their ends secured together, a rigid and ef-
25 fective canopy support for an insect netting and sunshade is provided, said head block and lateral frame being constructed so that the same may be manipulated as a unit, whereby upon removing the head block from
30 its standard and disconnecting the ends of the bars composing the lateral frame, the bars composing the frame structure can be folded or knocked down into a compact package of small compass, which can be
35 readily transported or shipped to any desired point.

My invention consists further of a novel construction of a standard having a foot or base member of novel construction, said
40 standard being provided with sleeves, which serve to support one or more shelves inter-locked therewith, one of said sleeves being adapted to support an electric light.

My invention further consists of a novel
45 construction of a head block having recesses and abutments therein, which serve to limit the movement of the outer bars which compose the canopy or screen supporting frame, means being also provided for pivotally sup-
50 porting diagonal bars and for holding the central laterally extending bar rigidly, so that the contiguous bars can be readily folded thereupon or thereagainst.

It further consists of a novel construction

of a frame composed of jointed bars mounted in a head block of novel construction, the construction and collocation of the bars being such that when the frame is unfolded or in operative condition, a rectangular canopy or screen support having intermediate angularly arranged bars of great strength and rigidity is provided.

It further consists of novel means for enabling the standard of my device when not desired to be utilized as a canopy or screen support, to be utilized in winter as a portable bedside appliance for serving drinkables and eatables in a bedroom or sickroom, the standard being further adapted by the provision of hooks thereon to be employed as a garment supporting device, my device thus being capable of being utilized in hot weather as a canopy or mosquito netting support, and in cold weather as a bedroom or sickroom appliance, it being apparent that the component parts composing my invention which are not used in winter are so connected and collocated with respect to each other as to admit of their being disconnected from the standard and taken apart and folded up or packed away in a comparative small storage space.

It further consists of a novel construction of standard, head block and canopy support or frame especially adapted as a support for a fly or mosquito screen, whereby the screen or netting is supported in position by its contact with the frame and all hooks, pins or the like are dispensed with, which precludes the screen from being torn or injured while being positioned upon or removed from its supporting frame.

It further consists of other novel features of construction and advantage, all as will be hereafter fully set forth and pointed out in the claims.

For the purpose of illustrating my invention, I have shown in the accompanying drawings forms thereof which are at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a portable standard and canopy support and its adjuncts embodying my invention, the netting or screen being removed therefrom.

5 Figure 2 represents a perspective view showing the netting or insect screen positioned upon its lateral supporting frame, and showing the flaps of the screen open.

10 Figure 3 represents on a reduced scale a front elevation of Figure 2, showing the screen or netting in closed position and the sunshade superimposed upon the top of the insect netting.

15 Figure 4 represents on an enlarged scale a plan view of Figure 1, showing the manner of assembling the outer and inner angularly disposed bars composing the lateral supporting frame for the mosquito netting or the like.

20 Figure 5 represents on an enlarged scale a section on line 5—5 Figure 7, showing the manner of providing the abutments for the two outer bars and the means for holding the central bar stationary with respect to the head block.

25 Figure 6 represents a plan view of the head block and the bars or frame members in folded or knocked-down position.

30 Figure 7 represents a side elevation of Figure 6.

Figure 8 represents a perspective view showing the manner of attaching a shelf to its sleeve.

35 Figure 9 represents a side elevation of a standard with the head block and canopy frame removed, showing the device as adapted to be equipped with an electric light, lateral shelves and garment supporting hooks.

40 Similar numerals of reference indicate corresponding parts.

Referring to the drawings:—

My invention in its broad aspects comprises a standard having a novel base, and 45 a novel head block, which carries pivotal jointed bars, which when open and secured in accordance with my invention, form a mosquito netting support and in carrying it out, I employ a suitable standard 1, having 50 a substantial base member 2 of such rigidity as effectively to support the upper detachable head or head block, which carries the laterally extending frame or jointed bars on which the canopy or netting is supported, said standard being preferably hollow for the purposes of lightness and rigidity, and being detachably secured at its lower end to said base 2, which has the feet or 55 foot members 3 and 4 projecting from opposite sides of said standard. The front foot member 4 is composed of the central web or member 5 having the bifurcated or forked terminals 6, which project laterally inwardly a considerable distance further from the 60 standard than the opposite terminals 7 of

the rear foot member 3, by which construction a very rigid and effective supporting base is produced which rigidly sustains the weight of the canopy frame and canopy.

Before the standard is inserted in the base, 70 I insert it through the upper and lower sleeve members 8 and 9, which are held at the desired height on the standard by the set screws 10 and 11 respectively, the upper sleeve 8 carrying an electric light bracket 12, having the electric light 13, while the lower sleeve 9 carries the shelf or leaf 14, which can be assembled with respect to its supporting sleeve in any suitable manner.

I preferably provide the lower sleeve with 80 ways comprising a vertical or longitudinal groove 15, preferably of dovetail shape in cross section and having at its bottom the pin or abutment 16, as seen in Figure 8.

To the underside of the shelf 14, I secure 85 the elongated bracket or arm 17, which terminates in the head 18, which has the vertical dovetail tongue 19, whose contour corresponds to the dovetail groove 15, said tongue having the bottom curved seat 20, 90 (see Figure 8), which rests on the abutment 16, so that when said tongue and groove are assembled, the shelf will be rigidly supported in horizontal position and locked against downward or sidewise movement. If desired, I may employ two shelves of different sizes, the larger shelf being designated as 95 21. Both shelves may be located below the light, as seen in Figure 1, or the smaller shelf may be located above the light and the larger shelf below the light, as seen in Figure 2, and said lower shelf can serve as a desk or table for writing, serving refreshments or for other purposes. The manner of attaching and supporting both shelves 100 14 and 21 is the same and will be understood from Figure 8.

The upper end of the standard 1 is provided with a reinforcing ring or collar 22, and within the opening or seat 23, at the 110 upper end of said standard, I insert the bottom stem 24 of the head block 25, which is held in position by the set screw 26. The head block 25 is of special construction, since it is necessary for the same to be of 115 sufficient rigidity to support the laterally extending jointed bars, which constitute the frame 44 which supports the canopy or netting, and the superimposed sunshade, and it is also necessary for the head block to be 120 internally so constructed as to enable said bars to be pivotally supported therein in such a way as to provide abutments to limit the outward movement of the two outer or rear bars of the frame, so that said bars 125 align when in open position, and to retain in fixed position the central bar of the frame, so as to facilitate the folding or knocking down of the other bars of the frame against each side of said central bar 130

when it is desired to fold up the frame into a small compact package for convenience in storage or transportation.

The head block 25, as will be understood from Figures 5 and 7, has oppositely located side recesses 26 therein, which are provided with the opposite walls, stops or abutments 27, best seen in Figure 5. The outer or rear bars 28 are pivoted at the points 29 within the recesses 26, so that said bars swing or stand horizontal at all times, and when said bars are in their unfolded position, as seen in Figures 1, 4 and 5, they are in alignment and their outer terminal edges contact with the walls or abutments 27, so that their extent of movement is limited or arrested when they are in alignment, as will be understood from Figure 5. The central bar 30 is rigidly secured by the pin 31 in the seat formed between the walls 32 best seen in Figure 5, whereby said central bar 30 is held immovably in position with respect to the head block 25. The diagonal bars 33 when the frame is in unfolded or operative position, as seen in Figures 1 and 4 extend radially from the head block 25 and to the outer end of each bar 33 is pivotally secured the outer end of the short bar 34 having the rabbeted end 35, and under this bar 34 is secured the outer end of the bottom or side bar 36, the outer ends of the bars 33, 34 and 36, which are arranged in pairs on opposite sides of the central bar 30 being pivotally secured by the common pin or threaded stem 37, which is provided at its bottom with a wing nut 38, as will be understood from Figure 7.

The inner ends of the diagonal or radial bars 33 are pivotally mounted in the head block at the points 39. The outer ends of the bars 28 are provided with the threaded stems 40, which are engaged by the wing nuts 41. The outer end of the central fixed bar 30 and the rabbeted juxtaposed inner ends of the outer bars 34 which overlap, are secured in open or assembled position, seen in Figures 1 and 4, by means of the threaded stem 42 having the wing nut 43.

The position that the bars constituting the frame 44 assume when in their open or operative position will be understood from Figures 1 and 4, the two rear bars 28 being in alignment and their extent of outward movement being limited by the abutments 27, while the two bars 34 are also in rectilinear alignment and are parallel to the bars 28. The side bars 36 are at right angles to the bars 28 and 34 and are parallel with each other, and by the employment of the diagonal bars 33, whose outer ends are connected to the bars 34 and 36 by the common fastening means 37, it will be apparent that an extremely light, rigid and durable, horizontal or laterally extending skeleton or frame is provided, which when in its open or opera-

tive position, as seen in Figures 1 and 4, forms a rectangular canopy support, which is effectively braced by the intermediate bars 33 and 30.

When the wing nuts 41, 43 and 38 are unscrewed, the two pairs of bars 28 and 33 and their adjuncts can be folded against the central stationary bar 30, so that the bars and the head block 25 can be handled as a unit, as will be understood from Figures 6 and 7, and can be readily packed in small compass for stowage or transportation purposes.

The head block 25 having been secured to the upper end of the standard 1 by the set screw 26^x, and the frame 44 composed of the bars 28, 36, 34, 33 and 30 having been unfolded or assembled, as seen in Figures 1 and 4, the canopy or mosquito netting or screen 45 is then placed in position, and as will be understood from Figures 2 and 3, a very effective screened enclosure is provided which while permitting the ingress of light and air, will effectively prevent the ingress of insects or the like.

In order to prevent the sun rays from entering the top of the inclosure formed by the walls of the screen 45, I employ a sun-shade or top 46 of suitable material, which can be provided with the depending scalloped flaps 47, which will give an ornamental appearance to the entire device.

By the provision of the rigid rectangular frame 44, it will be apparent that the netting 45 will automatically drape itself, so as to form a substantially rectangular screened inclosure of ample size, as seen in Figure 3, the front flaps as 48 and 49 overlapping when they hang vertically, and the screened inclosure is closed, as seen in Figure 3, or said flaps can be thrown back as seen in Figure 2, when it is desired to have ingress or egress to or from the screened enclosure. The bottom edges of the netting can be weighted as at 53 and secured to the ground or lawn at intervals, as at the points 50, by tent stakes, pins or the like, so that no insects can enter under the bottom of the netting.

In assembling the frame 44 with respect to its standard, I cause the frame to project in the same lateral direction as the elongated feet 6, so that the weight of the upper frame and its superposed netting will be effectively supported on said elongated feet 6, so that there will be no liability of the frame or standard toppling over. The lower end of the standard is secured in its base by any suitable means as the set screw 52, said standard being readily removed from said base upon loosening said set screw.

It will be seen from the foregoing that my device is readily adapted to a variety of uses, since it may be erected on the lawn or on a sleeping porch, camp or any other desired point.

4. In cold weather, when it is not desired to use the device as an insect screen, the screen and sunshade can be removed and the head block 25 and its adjuncts can be removed 5 from the standard and knocked down or folded up, as seen in Figures 6 and 7. The standard can be equipped with the garment hooks 51 and employed as a bedroom appliance or clothes-pole upon which to hang garments.

10 The standard 1 with the head block and its adjuncts removed will be especially adapted to use in a bedroom or sickroom, as said standard can be placed in proximity to the bed, and the light 13 employed for reading or writing purposes, and one of the shelves, as the larger shelf 21, can be employed as a table to support refreshments thereon, said table being readily adjusted 15 vertically to the height of the bed, and when through using the table, the latter if desired can be readily disconnected from its support, as will be understood from Figure 8.

15 My novel device is thus adapted to be utilized in whole or in part at all seasons of the year, and is most efficient for the purposes intended.

20 Having thus described my invention, what I claim as new and desire to secure by Letters Patent, is:—

25 1. In a device of the character stated, a standard, a head block therefor provided with oppositely located recesses, a foldable canopy supporting frame composed of a central bar fixedly secured in said head block, and rear bars and diagonal bars having their 30 ends pivotally mounted in said head block,

and means for securing the outer ends of the bars when unfolded together so that a polygonal canopy frame is formed.

2. In a device of the character stated, a detachable head block having oppositely located recesses therein and a pendant stem for enabling said head block to be mounted on a standard, a knock-down frame carried by 45 said head block and comprising a central bar fixedly secured in said head block, rear bars pivotally mounted in the recesses in said head block, said recesses being provided with walls serving as abutments to retain said 50 rear bars in alignment when open, a pair of diagonal bars pivotally mounted in said head block, and side and front bars secured by a common pivot to the outer ends of said diagonal bars, whereby a rectangular canopy 55 frame is formed when said bars are in unfolded position and their outer ends are secured together.

3. A skeleton frame for a canopy or netting, composed of a head block, a central bar 60 30 fixedly secured therein, rear bars 28 pivot in said head block, diagonal bars 33 pivot in said head block, side bars 36 and front bars 34, said bars 34, 33 and 36 having their outer ends secured by a common pivotal connection, said bars 28 and 36 being pivoted together, and the juxtaposed ends of said bars 30 and 34 being fastened together.

LILLIAN D. STOCKLE.
